SPARK PLUG SHIELD

George G. Burrell and Leo Burrell, Cedar Rapids, Iowa; said Leo Burrell assignor to Kittle P. Burrell, Cedar Rapids, Iowa

Application March 8, 1946, Serial No. 652,887

10 Claims. (Cl. 174—77)

1

This invention relates to spark plugs, and particularly to means for moisture proofing the electrical connection to such plugs.

Although numerous methods and devices have been suggested for moisture proofing spark plugs, most of such devices require a complicated structure and many of them involve the use of a completely new spark plug with a moisture shield built as an integral part of the plug. Since the spark plugs used in motor vehicles are, for the most part, still of the type embodying an exposed porcelain insulator, it is a primary object of our invention to provide a simple adapter, for use in conjunction with such plugs, for protecting the electrical connection to the plug from shorting out and becoming in-operative due to rain or condensation or other causes.

Another object of our invention is to provide a device which may be manufactured very inexpensively to serve this purpose and one which may be readily applied to a spark plug of ordinary construction.

A further object of our invention is the provision of an improved and simplified means for providing a seal between a moisture shield and the porcelain insulator of a spark plug.

Other and further features and objects of the invention will be more apparent to those skilled in the art upon a consideration of the accompanying drawings and following specification, wherein are disclosed several exemplary embodiments of the invention, with the understanding, however, that such changes may be made therein as fall within the scope of the appended claims, without departing from the spirit of the invention.

In the drawings:

Figure 1 is a view in elevation of a spark plug embodying a moisture shield constructed in accordance with our invention.

Figure 2 is a view partly in elevation and partly in section of the device shown in Figure 1.

Figure 3 is a view in perspective of a modified form of a sealing washer which may be embodied in our invention.

Figure 4 is a view partly in elevation and partly in section of a slightly modified form of the moisture shield shown in Figures 1 and 2, and

Figure 5 is a view in elevation, partly in section of another modified form of our invention.

Referring now to these drawings and to Figures 1 and 2 thereof in particular, the spark plug indicated generally at 1 includes the main body portion 2, the threaded portion 3, and a porcelain insulator 4, extending generally upwardly through the center of the body. The threaded terminal 5

2

at the top of the insulator, is a portion of the electrical conductor which extends downwardly through the center of the insulator to terminate in the firing point 6.

5 In the majority of such plugs the porcelain insulator 4 is provided with one or more annular corrugations or enlargements 7, and we propose to employ these enlargements as an aid in sealing the plug against moisture as will be herein-after described.

A pointed stylus 8 is provided with a tapped opening 9, on its under side, to permit attachment to the central terminal 5. This stylus, being adapted to penetrate the lower end of the ignition cable 10, serves both to contact the conductor 11 within the cable and to expand the lower end of the cable as indicated at 12.

The conical moisture shield 13, preferably of molded plastic or the like, is apertured at its upper end, as at 14, for the reception of the cable 10, and this opening is of such a size as to closely engage the cable, and it will be apparent that, when the stylus is forced upwardly into the cable 10, the lower end of that cable will be wedged and sealed within the opening 14.

The lower end of the moisture shield 13 is threaded internally, as at 15, for the reception of the externally threaded, lower insulating shield or sleeve 16. An opening 17, extending through the center of this sleeve, is of such size as will permit it to be received over the porcelain of the plug. A washer 18, of such an outside diameter as will permit it to be received within the lower end of the shield 13, has a centrally disposed opening 19 of a size somewhat less than the diameter of the enlarged portion 7 of the porcelain. This central opening 19 may be approximately the same size as the diameter of the constricted portion of the plug immediately below the enlargement 7, and this sealing washer 18 is split, preferably diagonally as indicated at 20, to permit the washer to be forced onto the top of the plug over the corrugation or enlargement.

With the various parts of the device assembled as shown in Figure 2, the cable 10 will be sealed within the opening 14 at the upper end of the moisture shield 13 and the sleeve 16, when screwed upwardly against the under surface of the washer 18, will provide a seal against that surface. The washer itself will be forced into intimate contact with the porcelain and thus provide a seal against the curved under surface of the porcelain enlargement 7.

A modified form of sealing washer such as illustrated in Figure 3 may be employed in the struc-

ture of Figure 2. The washer, instead of being split diagonally as indicated at 28 in Figure 2, is composed of 2 separate members 21 and 22, each member actually being a complete washer in itself and each split radially as indicated at 23 and 24. These cuts 23 and 24 are staggered radially to provide a leak-proof joint.

The slightly modified form of our invention as illustrated in Figure 4 is substantially the same as the structure shown in Figures 1 and 2 in that the structure includes the complete spark plug with the porcelain 4, the upper terminal 5, the enlargement 1 on top of the porcelain, and the cable 10. The moisture shield 25 is of somewhat different shape than the structure shown in Figure 2. It is provided with the opening 26 through its upper portion for the reception of the cable 10, but the inner cavity 27 tapers toward the hole 26 in such a manner that the lower end of the cable 10 is wedged against the tapered side walls of the cavity 27 as well as in the hole 26. The lower end of the moisture shield 25 is threaded externally as at 28, to receive the internally threaded, lower insulating shield or sleeve 29. This sleeve is flanged inwardly at its bottom, as at 30, so as to carry the sealing washer 31. This sealing washer is split diagonally, as shown at 32, or a double washer such as we have shown in Figure 3 is employed to permit its installation over the enlarged portion of the spark plug porcelain. Both the moisture shield 25 and the sleeve 29 are preferably provided with drip flanges 33 and 34 respectively.

Figure 5 illustrates a form of our invention adapted for use with spark plugs of the type having a porcelain with a smooth cylindrical upper end—and without the corrugations or enlargements shown in Figures 2 and 3. Such a plug is indicated at 35 with the porcelain insulator 36 and upper terminal 37.

This form of moisture shield generally comprises the upper shield 38, the lower shield 39, the gasket 40 and the stylus 41. The upper shield 38 is in the form of a hollow shell apertured at its top, as at 42, to receive the ignition cable 43 and threaded internally at its lower end, as shown at 44. This lower end engages over the externally threaded upper end of the lower shield 39. The lower shield is cylindrical with its lower end open for reception over the upper end of the porcelain 36 and the upper wall 45 of the lower shield is apertured, as at 46, to permit the plug terminal to pass upwardly through the shield.

The interior of the lower shield is provided with a shoulder 47 against which the washer 40 is adapted to bear. The stylus 41 is drilled and tapped for the upper terminal as in Figure 2, but its lower end is preferably cut back to provide a shoulder for engaging the upper wall of the lower shield.

The gasket 40 has an internal diameter suitable to the porcelain over which it is to be placed and, when assembled as illustrated and forced down over the porcelain by screwing the stylus into place, the gasket will seal the upper end of the porcelain.

The electrical connection between the stylus 41 and the cable 43 is, of course, sealed against moisture when the upper shield 38 is threaded onto the lower shield 39.

Although we have described specific embodiments of our invention, it is apparent that modifications thereof may be made by those skilled in the art. Such modifications may be made with-

out departing from the spirit and scope of our invention as set forth in the appended claims.

What we claim is:

1. In a moisture shield for a spark plug having a porcelain insulator and a terminal at the top thereof, an upper insulating shield having an opening through the top thereof for receiving an ignition cable, means including a stylus for expanding and sealing a cable within the said opening, a lower insulating shield member threadedly engaged to the said upper shield and a sealing gasket engaged by and adapted to be forced by the lower shield member into contact with the porcelain insulator whereby a moisture sealed chamber is provided above the said sealing gasket and within the upper and lower insulating shields.
2. In a moisture shield for a spark plug having a porcelain insulator, a shield, a cable received through an opening in the top of the shield, a pointed stylus, means forcing the stylus into the cable to wedge and seal it within the opening, and means cooperating with said shield to provide a moisture-proof chamber enclosing the top portion of the insulator, said means including a split washer associated with the shield at its lower end and resiliently engaging the porcelain insulator.
3. For use in combination with an insulated ignition cable and a spark plug including an insulator having an annular enlargement thereon and an electrode disposed centrally of the insulator; a pointed stylus secured to the said electrode, a hollow shield having an opening in the top thereof for receiving the cable, means forcing the said stylus into the end of the cable to expand and seal the cable within the shield opening, said means comprising a sleeve threadedly engaged to the said shield and a split washer engaged by the said sleeve and mounted over and engaged beneath the insulator enlargement.
4. The combination of a cable and a spark plug including an insulator and an electrode disposed centrally of the insulator, a stylus secured to the electrode, a shield having an opening through the top thereof for receiving the cable, means forming a shoulder adjacent the top of the insulator, a split washer engageable beneath the shoulder and a sleeve engaging the said washer and threadedly engaged with the said shield, the said stylus adapted to make contact with the cable and to wedge and seal it in place within the shield opening.
5. In a moisture shield for spark plugs, the combination with a spark plug insulator, of a shield for covering the upper portion of the said insulator, an enlargement provided adjacent the top of the insulator and means for sealing the lower end of the shield including a washer split to permit it to be installed over the insulator enlargement and adapted to engage the said enlargement on its under side.
6. In a moisture shield for spark plugs, the combination with a spark plug insulator having an enlargement adjacent the top thereof, of a shield for covering the upper portion of the said insulator, and means for sealing the shield at its lower end including a washer, split angularly to permit it to be installed over the insulator enlargement and adapted to engage the said enlargement on its under side.
7. For use in combination with an insulated ignition cable and a spark plug including a porcelain insulator having an annular enlargement thereon and an electrode disposed centrally thereof, a pointed stylus removably secured to the

upper end of said electrode, a hollow and generally downwardly and outwardly flaring moisture shield of an insulating material, the said shield having an opening through its top of substantially the same diameter as that of the cable, the said stylus adapted, when forced upwardly, to penetrate and expand the lower end of the ignition cable to wedge and seal the cable within the said opening, and means for sealing the lower end of the said moisture shield and forcing said stylus into engagement with said cable comprising an insulating sleeve threaded into the lower interior of the said shield and a split sealing washer, the said sleeve having an opening therethrough larger than the insulator enlargement and the split washer having an opening therethrough smaller than the insulator enlargement.

8. In combination with an insulated ignition cable and a spark plug including an insulator having an annular enlargement adjacent the top thereof and an electrode disposed centrally thereof, an insulating moisture shield adapted to cover the entire upper portion of the insulator and having an opening in its top for the reception of the cable, a pointed stylus secured to the top of the electrode, a split washer having an opening therethrough of smaller diameter than the outer diameter of the annular enlargement and adapted to be positioned below said enlargement, a sleeve threadedly engaged to the lower end of the moisture shield and adapted to engage the said washer whereby engaging the sleeve to the shield will seal the said washer against the enlargement and force the stylus into the cable to enlarge it and wedge and seal it within the opening in the shield.

9. In a moisture shield for a spark plug having an upper terminal and a porcelain insulator the upper portion of which is of generally tapering shape, a hollow lower shield having an opening through the top thereof adapted to be received over the terminal, the lower shield having a shoulder on the interior thereof, a gasket, having an opening through the center thereof of lesser

10 diameter than the largest diameter of the porcelain, adapted to rest against the said shoulder, a stylus engageable with the upper terminal and adapted to force the lower shield downwardly to thus force the said gasket into a sealing contact with the porcelain, an upper shield having an opening through the top thereof to receive an insulated cable, and means for removably securing the said upper shield to the said lower shield.

15 10. In a moisture shield for use with an ignition cable and a spark plug having an insulator and an upper terminal, a lower shield having a recess in the bottom thereof and having an opening through the top thereof for reception over the terminal, a flexible sealing member adapted to form a seal against the lower shield within the recess and adapted to seal against the insulator of the plug at a point below the terminal, a pointed stylus engageable with the upper terminal and adapted to force the said sealing member, the insulator and the lower shield into a sealed relationship, an upper shield threadedly engaged to the lower shield and having an opening through the top thereof for receiving an insulated cable, the pointed stylus being of such length as to penetrate and expand the lower end of such cable within the opening in the top of the upper shield.
